UNITED STATES PATENT OFFICE.

WILLIAM THEGEN, OF PHILADELPHIA, PENNSYLVANIA.

DESIGN FOR A BADGE.

SPECIFICATION forming part of Design No. 16,099, dated May 19, 1885.

Application filed April 18, 1885. Term of patent 3½ years.

To all whom it may concern:

Be it known that I, WILLIAM THEGEN, a citizen of the United States, residing at Philadelphia, in the county of Philadelphia and 5 State of Pennsylvania, have invented and produced a new and original Design for Badges, of which the following is a specification, reference being had to the accompanying drawing, forming part thereof, and wherein the to badge embodying the design is shown in elevation.

The said badge is of that species wherein the portion to be directly attached to the person of the wearer is provided with a dependent band of ribbon supporting a bottom cross-bar and charm or pendant.

In my design the top portion, A, is shaped in imitation of a crown or coronet, having a lower band, a, a second band, b, lozenges between the two bands, and from the band b, which is in the shape of a twisted cord, a double series of projections, c c'. The series c terminate in a corresponding number of balls, d, and on the face of the crown is the figure of 25 a star, f.

The band D is plain.

The lower cross-bar, B, is provided with a central circular opening surrounded by a

raised band, e, from which extend laterally scalloped or curved arm extensions g, and beneath said band is located foliate ornamentation h.

The pendant C is shaped like a star, and has an inner opening of like shape. It has raised edges bounding its periphery and surrounding the inner opening. Between these edges it is ornamented with scroll-work and arbitrary lines, and at its point of union with the cross bar B other scroll-work surmounted by a ring is located.

Having thus described my invention, I 40 claim—

The design for badges herein shown and described, consisting of a top piece shaped like a crown or coronet and bearing a star, the 45 plain portion D, the cross-bar B, provided with a plain center, and with ornamental wing-extensions, and the pendant C, of star shape, and having a star-shaped opening, raised edges, and ornamental scroll-work between such edges, substantially as described and shown.

WM. THEGEN.
